Primary Examiner — Michael C Stout*Assistant Examiner* — Melvin L Davis(74) *Attorney, Agent, or Firm* — Calderon, Safran & Cole P.C.(57) **CLAIM**

The ornamental design for a block toy figurine, as shown and described.

DESCRIPTION

FIG. 1 is a front upper perspective view of my assembling block toy;

FIG. 2 is a front elevational view;

FIG. 3 is a rear elevational view;

FIG. 4 is a right side view;

FIG. 5 is a left side view;

FIG. 6 is a top plan view;

FIG. 7 is a bottom plan view;

FIG. 8 is a rear lower perspective view; and,

FIG. 9 is another lower rear perspective view.

The dashed lines in FIGS. 3, 7, 8 and 9 depict portions of the block toy figurine that form no part of the claimed design.
